UNITED STATES PATENT OFFICE.

JOHN S. ROWE, OF BUFFALO, NEW YORK.

DESIGN FOR A LAVATORY.

41,059.

Specification for Design.

Patented Dec. 27, 1910.

Application filed July 12, 1910. Serial No. 571,665. Term of patent 7 years.

To all whom it may concern:

Be it known that I, JOHN S. ROWE, a citizen of the United States, residing at Buffalo, in the county of Erie and State of New York, have invented a new, original, and ornamental Design for a Lavatory, of which the following is a specification.

The accompanying drawing, forming a part of this specification, is a perspective view of a lavatory showing the design.

The design comprises as its main features a washbowl having a depressed part form-

ing a basin, and an upright portion extending upwardly therefrom at the rear part of the washbowl and partly surrounding the basin, and a supporting pedestal on which the washbowl is mounted.

I claim:

The ornamental design for a lavatory, as shown and described.

JOHN S. ROWE.
